UNITED STATES PATENT OFFICE.

EDWARD E. CLEMENT, OF WASHINGTON, DISTRICT OF COLUMBIA, ASSIGNOR, BY MESNE
ASSIGNMENTS, TO FREDERICK C. STEVENS, OF ATTICA, NEW YORK,
FOR THE INVENTION OF A TELEPHONE-EXCHANGE SYSTEM.

1,145,120.

Specification of Letters Patent.

Patented July 6, 1915.

Application filed March 27, 1905. Serial No. 252,306.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object the arrangement of a system which shall centralize the labor of connecting subscribers as much as possible, shall divide apparatus and distribute cable as economically as may be, and shall accomplish sundry other purposes which will sufficiently appear from the detailed description hereinafter given.

15 In large cities it is not always practicable to serve all subscribers from one central point, on account principally of the difficulty and expense of cable distribution. Divided or branch exchanges are therefore maintained, with consequent division of operating and maintenance forces and consequent increase in pro rata expense. It is found that the percentage of expense to income is higher in divisions than it would be if the labor could be economically handled, 20 i. e. from one common center. On the other hand the saving in cable by a judicious division of exchanges is proportionately very large, as the number of trunks required to cover a given territory is necessarily less 25 than the number of individual lines.

30 According to the present invention I group my subscribers according to their location, and connect each group to a group or branch exchange. There are no operators at these branch exchanges, all the operators being located at one selected central point, which I designate the clearing house. Each branch exchange is equipped with automatic switches, and a suitable source of current supply, and is connected to the clearing house by as many trunk lines as may be required to carry the maximum load. A subscriber desiring a connection takes down his receiver, whereupon a switch at his branch exchange which forms the terminal of his line automatically connects him with an idle trunk line leading to the clearing house, and there his call becomes apparent to an operator, since the trunk lines all terminate like ordinary 35 subscribers' lines in an old-fashioned mul-

40 tiple switch board, on answering jacks, with which are associated line signals. The operators handle the trunks as they would subscribers' lines, receiving the calls and connecting without any difference; but each operator has an impulse transmitter, or if necessary several, by which she selects the subscriber wanted at the branch exchange to which the trunk she connects with, is led. I have indicated my trunks as two way trunks, serving both for in and out messages, but obviously they can be separated as to their functions.

45 The switches Z' and Z^{1-2} which I have shown in diagram and which I use are similar to those shown in the Keith and Erickson Patents No. 815,176, dated March 13, 1906, and No. 815,321, dated March 13, 1906, with the exception that I use more wipers and more contacts which only amounts to multiplication. The switches Z and Z^2 make use of a rotary spindle similar to that of the switches shown in the patents cited, this being a common mechanical expedient in automatic systems.

50 My invention includes many details of construction, which will appear from the following description and claims.

55 My invention is illustrated in the accompanying drawings, wherein—

Figure 1 shows the subscriber's station terminating in a selector switch at a sub-exchange or station, also the sub-exchange end of the central office trunk containing the connector switch. Fig. 2 is a similar diagram showing the central office ends of two two way trunks, one being used to illustrate an incoming call, the other for an outgoing call. The cord-circuit is also shown, which forms the connecting link between these trunks. Fig. 3 is a duplication of Fig. 1, and is used to illustrate a two way trunk being used for an outgoing call, Fig. 1 illustrating a two way trunk being used for an incoming call.

60 The apparatus and wiring in both Figs. 1 and 3 being identical, the same lettering is observed throughout.

65 Referring now to Fig. 1, A is the subscriber's station equipped with apparatus usual in common battery systems. It consists of transmitter T, receiver R, hook H, ringer Q and condenser C. The line-wires 1 and 2 from this station terminate in the wipers z' and z^2 of the selector switch Z,

which has associated with it the following: the line-relay M, retardation coil N', which supply battery current for talking and signaling; relay S, actuated by the relay M, which controls the vibrating or rotary magnet s; relay S' controlled by the wiper z^{14} of the trunk connector Z' for outgoing calls; release magnet W controlled jointly by the relay M and the contact springs z^1 , z^3 , operated mechanically by the spindle z; trunk connector switch Z', which can be any form of a standard switch responding to the vertical and rotary impulses from a transmitting device. In this case I have used the switch commonly known as the Strowger switch, which consists of the following: vertical relay S⁷, rotary relay S⁸, test relay X, ringing relay Y, vertical magnet s^{34} , rotary magnet s^{35} and release magnet W². In addition to this apparatus I have added the cut-off relay S⁹ for the purpose of cutting off the vertical and rotary relays S⁷ and S⁸, respectively, and short-circuiting the condensers C², C³, while the trunk is being used. I have also added the wiper z^{11} connected to one terminal of the relay S⁹ by the wires 10 and 69. There is also added the additional wiper z^{14} connected to battery for the purpose of cutting off the operating mechanism of the line selector switch in outgoing calls by energizing the relay S'. The springs z^{15} and z^{16} are controlled by the spindle z^9 when it steps up into vertical position for the purpose of making the trunk busy for an incoming call.

Referring now to the first selector switch Z, one terminal of the line-relay M is connected to wire 1 by wire 3, the other terminal being grounded. The contact m^4 is connected to the multiple-contact z^{23} , of the trunk connector switch by the wire 8. This same contact is also connected to the contact s^2 of the relay S', and from there to the winding of the relay S by the following path: contact s^3 , wire 7, contacts z^5 , z^6 , wire 14, relay S. It is also connected to the front contact s^7 of the relay S by the wires 12 and 7. The contact m^3 is connected to the multiple-terminal z^{24} by wire 18. The contact m^2 is connected to the release magnet W by the following path: wire 6, contacts z^7 , z^8 , wire 16, and magnet W. The retardation coil N' is connected to the line-wire 2 by the wire 4 and to battery B by wire 23. One terminal of the relay S' is connected to the multiple-contact z^{25} , in the trunk connector switch by the wire 9, the other terminal being grounded. One terminal of the relay S is connected to battery by the wires 10 and 23, the other terminal as before stated being connected to the contact m^4 of the relay M. The contact s^5 is connected to the rotary magnet s by the wire 11. The contact s^6 is connected to the wiper z^3 by the wire 13, and the wiper z^4 is grounded.

Referring now to Fig. 2, the central office end of the trunk from the sub-station terminates in springs j and j', respectively, of the jack J. The trunking apparatus consists of the signal relay M', one terminal of which is connected to the trunk-wire N. 20 by the wire 26, the other terminal being grounded through the wire 25, contacts n^1 and n^2 of the cut-off relay N. The relay M' jointly controls the busy lamp n and directly controls the signal lamp m. One terminal of the cut-off relay N is connected to the thimble j^2 of the jack J by the wire 32, the other terminal being connected to battery by the wire 27. Relay N jointly controls the busy lamp n and disconnects the signal relay M', when energized. I have thus described the central office end of the incoming trunk; and as the central office end of the outgoing trunk is identical it will need of no description. The cord-circuit consists of the following: the answering plug P, calling plug P', supervisory relay S², retardation coil I, controlling relay S⁴, answering supervisory lamp s¹, calling supervisory relay S³, retardation coil I', controlling relay S⁵, calling supervisory lamp s¹⁰, automatic trunk disconnect relay S⁶. The tip p of the answering plug P is connected to the tip p' of the calling plug P' by the following path: strand 21, contacts k, k' of the listening key K, condenser C, contacts k¹ and k² of the key K' and strand 23. The sleeve p of the answering plug P is connected to the sleeve p' of the calling plug P' by the following path: strand 22, contacts k² and k³ of the listening key K, condenser C', contacts k⁶ and k⁷ of the key K' and strand 24. The relay S² is connected to the strand 21 by the wire 36 and to ground by the wires 3 and 34. One terminal of the retardation coil I is connected to the strand 22 by the wire 37, the other terminal being connected to ground through the wires 35 and 36. Contact s^{16} of the relay S² is connected to the supervisory lamp s¹⁰ and the contact s^1 of the relay S³ by the wire 43 and from there to battery, through wire 44. The contact s^{16} is connected to one terminal of the relay S⁶ and contact s^{22} , the other terminal of the relay S⁶ being connected to the lamp s¹⁰, and the contact s^{18} of the relay S⁵ by the wire 41. Contact s^{20} of the relay S⁶ is connected to the strand 24, and contact s^{21} connected to the strand 23 by wire 38. The contact s^{19} is connected to battery by the wires 45 and 44, and one terminal of the relay S³ is connected to the strand 23 by wire 38, the other terminal being connected to ground through the wire 40, and contact s^1 is connected to battery by wire 44. One terminal of the relay S⁵ is connected to the third conductor p² of the calling plug P' by wire 46, the other terminal and the contact s^{17} being connected to ground. Fig. 3 bei-

identical with Fig. 1, will need of no description, but the operation will be explained in the proper order.

The operation of my system is as follows: Referring now to Fig. 1, the subscriber removing his telephone closes the circuit of the line-relay M, which attracts its armatures and closes the circuit of the relay S by the following path: ground, contacts m' , 10 m^4 , wire 8, contacts s^3 , s^2 of the relay S', wire 7, contacts z^5 and z^6 , wire 14, relay S to battery. The relay S then being energized attracts its armatures and closes the circuit of the rotary-magnet s by the following path: battery B, wires 23 and 10, contacts s^4 , s^5 , wire 11, magnet s, contact s' to ground. The magnet s thereupon begins to vibrate causing the spindle z , carrying the wipers z^1 , z^2 , z^3 and z^4 to rotate. The instant this switch begins to rotate, the contacts z^5 , 20 z^6 are broken, which opens the circuit between the winding of the relay S and the contact m^1 of the relay M. The relay S, however, is not deenergized until the proper 25 time, or until the wiper z^3 in passing over the multiple-contacts z^{19} fails to find a grounded one, it being held up in the meantime on account of these grounded contacts coming into connection with wiper z^2 , which is connected to the contact s^6 , which is now engaged with the contact s^8 through the winding to battery. When the wiper z^3 finds an idle contact, that is one free from ground, the relay S becomes deenergized, opens the 35 contacts s^4 and s^5 , which disconnects the vibrating or rotary magnet s. When the spindle z first began to rotate, it closed the contacts z^7 , z^8 , which placed the release magnet W under the control of the calling subscriber by the following path: battery B, wires 23 and 15, W, wire 16, contacts z^7 and z^8 , wire 6, contact m^2 of the relay M. When the calling subscriber hangs up his telephone at the end of a conversation, the contacts m^2 and m' are closed, thus operating 45 the release magnet W. When the relay M was first energized it placed ground on the multiple contacts z^{23} of the connector switch trunk by the following path: wire 8, contacts m^4 , m' to ground. This makes this line busy for an outgoing call as in the Strowger system. At the same time a ground is placed in the multiple-contact z^{24} of the trunk connector switch by the following path: wire 55 18, contacts m^3 and m' to ground. This ground being placed on the contact z^{24} has no bearing on an incoming call, but on an outgoing call serves to energize the cut-off relay S⁹, cutting off the vertical and rotary 60 relays and short-circuiting the condensers in the connector switch during conversation. The instant the wiper z^3 found an idle contact, the relay S became deenergized and the 65 spindle z ceased to rotate. The wiper z^4

coming into contact with the terminal z^{20} energized the cut-off relay S⁹ of the connector switch Z', which disconnected the relays S⁷, S⁸, and also short-circuited the condensers C² and C³. The trunk leading to the clearing-house is now clear. The subscriber is now connected to an idle trunk leading to the central office or clearing-house by the following path: wire 1, wiper z' , contact z^{17} , trunk-wire 19; in Fig. 2, j of the jack J, wire 2, wiper z^2 , contact z^{18} , trunk-wire 20, and j' of the jack J. This connection being completed, the signal relay M', Fig. 2, is placed in series with the retardation coil N', Fig. 1, by the following path: 70 battery B, wires 23, 4, 2, contacts z^2 , z^{18} , wires 20 and 26, M', wire 25, contacts n' , n^2 of the relay N to ground. The relay M' thereupon becomes energized and attracting its armature causes the signal lamp m to 75 glow by closing the contacts m^5 and m^6 . The busy-lamp n is also caused to glow by closing the contacts m^5 and m^6 . This busy lamp is multiplied in each position and notifies the other operators that this particular 80 trunk is busy. The operator upon perceiving the line-signal inserts the answering plug P into the jack J causing battery to flow through the relay S⁴ and the cut-off relay N in series by the following path: 85 ground, wire 34, relay S⁴, wire 33, p^2 , j^2 , wire 32, N, wire 27 to battery. The relay N becoming energized attracts its armature, disconnects the relay M' by breaking the contacts n' and n^2 , extinguishing the line-signal m. The contacts n' and n^3 are closed, 90 causing the busy lamp n to continue glowing. The relay S² being in multiple with the line relay M, Fig. 1, is energized, attracts its armature, breaking the contacts s^{11} and s^{12} , preventing the lamp s⁹ from glowing, as this lamp circuit was completed by the closing of the contacts of the relay S⁴. The operator upon finding what number is desired inserts the calling plug P' into a trunk 95 jack J' leading to a connector switch in a sub-exchange containing the multiple contact of the line desired. This insertion causes battery to flow through the relay S⁵ and the relay N², in series, by the following path: 100 ground, S⁵, wire 46, p^2 , j^2 , wire 53, N², wire 51 to battery. The relay N² becoming energized attracts its armature and disconnects the line-relay M², and at the same time closes the contact leading to the busy lamp n⁴ 105 causing it and its multiple lamp in the other positions to glow, notifying the operators that this trunk is busy. The relay S³ becoming energized attracts its armature, causing the lamp s¹⁰ to glow and to continue to 110 glow until the called subscriber answers. The operator upon placing the calling plug P' into the trunk jack J' throws the lever of her key K' into contact with a dial or 115 automatic sender, which can be of any stand- 120

ard form, which will transmit impulses affecting the vertical and rotary relays in the connector switch. The operator will only have to manipulate her sender twice. 5 The first time to transmit the ten numeral of the line wanted and the second time the unit numeral of the line wanted, having in the meantime learned the thousand and hundred numeral of the line wanted from 10 the calling subscriber in answering the call. In operating her sender the first time, impulses are sent over the trunk wire 54, affecting the vertical relay S^7 in the connector switch Z^{12} at the sub-station, Fig. 3. These 15 impulses corresponding to the ten numeral of the line wanted affect the relay S^7 , correspondingly, which attracting its armature operates the vertical magnet s^{34} by the following path: ground, contacts s^{24} , s^{25} , wire 75, contacts x and x' of the relay X , wire 76, side switch z^{17} , wire 83, s^{34} , wire 81 to battery. The magnet s^{34} in operating causes the 20 spindle z^9 to step up in a vertical position carrying the wipers z^{10} , z^{11} , z^{12} , z^{13} and z^{14} to the desired row. After the last impulse 25 has come in over the wire 54, one impulse is sent in over the trunk-wire 55, affecting the relay S^8 , whereby it attracts its armature and energizes the relay X causing the side 30 switches to make one step, thus cutting off the vertical magnet s^{34} and in its place cutting on the rotary magnet s^{35} . It also connects the wiper z^{12} to the magnet W^2 through the side switch z^{20} and contacts x^2 , x^3 of the 35 relay X when it is energized.

The operator in operating her sender the second time transmits impulses over the trunk-wire 54 affecting the relay S^7 , which now in turn operates the rotary magnet s^{35} . 40 This rotary magnet while operating causes the spindle z^9 to rotate and come opposite the contacts leading to the desired line. After the last impulse has been sent in over trunk-wire 54, one impulse is sent in over the trunk-wire 55, affecting the relay S^8 , which operates the relay X . The relay X causes the side switches to make one more step which disconnects the rotary magnet s^{35} through the side switch z^{17} , grounds 45 the wiper z^{12} through the side switch z^{20} and connects the wire 56 to the wiper z^{10} by the following path: contacts y and y' of relay Y , wire 58, side switch z^{18} , wire 60, wiper z^{10} . It also connects the wire 57 to the wiper z^{11} by the following path: contacts y^3 and y^4 , wire 59, side switch z^{19} , wire 61, wiper z^{11} . The last movement of the side switch z^{11} cuts on the ringing relay Y and places it under control of the vertical relay S^7 50 by the following path: battery, wire 80, Y , wire 87, side switch z^{17} , wire 76, contacts x , x' of the relay X , wire 75, contacts s^{24} , s^{25} of the relay S^7 to ground. The trunk 55 terminal now resting on the desired line the operator pushes the ringing button connect-

ed to the dial, which closes the circuit of the relay S^7 over the trunk wire 54. This relay being energized, closes the circuit of the relay Y , which attracting its armature opens the wires 56 and 58, 57 and 59 and sends a generator current out over the wipers z^{10} and z^{11} to the line of the called subscriber. The spindle z^9 , Fig. 3, in making its first vertical step closes the contacts z^{13} , z^{16} , grounding the multiple contacts z^{19} in the banks of the line selector switches, making this particular trunk busy for incoming calls. The wiper z^{14} coming into contact with the terminals z^{25} energizes the relay S^7 of the line selector switch, causing it to attract its armature, disconnecting the starting mechanism of that switch, for it is evident that the relay M being energized when the called subscriber answered, the rotary magnet will at once start, and so the foregoing means are provided for preventing this. The wiper z^{13} leading to the cut-off relay S^9 is in connection with the terminal z^{24} , leading to the normally open contact m^3 of the line-relay M . The called subscriber upon answering closes the circuit of the line-relay M , which at once becoming energized closes the contacts m' and m^2 , energizing the cut-off relay S^9 , which attracting its armature disconnects relays S^7 and S^8 , respectively, by breaking the contacts s^{28} , s^{29} and s^{31} , s^{32} . It also short-circuits the condensers C^2 , C^3 , respectively, by closing the contacts s^{28} , s^{30} and s^{25} , s^{31} . The called subscriber is now connected straight through to the clearing house or central office over line-wire No. 1, by the following path: wire 5, z^{21} , z^{10} , wire 60, side switch z^{18} , wire 58, contacts y and y' of the relay Y , wires 56 and 64, contacts s^{30} , s^{21} of the relay S^9 , wires 62, 54, j and p of the calling plug P' , and over No. 2 side of the line by the following path: wire 17, z^{22} , z^{11} , wire 61, side switch z^{19} , wire 59, contacts y^3 , y^4 of the relay Y , wires 57 and 65, contact s^{23} , s^{31} of the relay S^9 , wires 63 and 55, j and p' of the calling plug P' . The relay S^3 , Fig. 2, being in multiple with the line relay M , Fig. 3, of the called subscriber line, became energized when he removed his telephone, which extinguished the lamp s^1 notifying the operator at the clearing-house that the call is answered. At the end of the conversation, calling subscriber hanging up his telephone opens the circuit of the lines 1 and 2, which deenergizes the line-relay M , closing the contacts m' and m^2 . The release magnet W is now energized and attracts the latch w , releasing the spindle which swings around in its normal position, opens the contacts z^7 , z^8 , disconnecting the release magnet W , and closes the contacts z^5 and z^6 , closing the circuit of the relay, placing it under control of the line-relay for another call. The wiper z^4 leaving the

contact s^{20} opens the circuit of the cut-off relay S^9 of the trunk connector switch Z' , which again connects the relays S^7 and S^8 , respectively, to the trunk wires 54 and 55. The short-circuit is now also removed from the condensers C^2 and C^3 .

Referring to Fig. 2, the relay S^2 also becomes deenergized and the circuit of the lamp S^9 is closed, causing it to glow, notifying the operator that the calling subscriber has hung up his telephone. The contacts s^{15} and s^{16} are now closed and the relay S^6 has its circuit partly completed by the following path: ground, contacts s^{17} , s^{18} of the relay S^5 , wire 41, S^6 , contacts s^{15} , s^{16} , wire 43 to the contact s^{14} of the relay S^3 . The called subscriber in hanging up his telephone opens the circuit of the line-relay M of the line selector switch Z^2 , Fig. 3, which becoming deenergized opens the contacts m' , m^3 , releasing the cut-off relay S^9 of the connector switch Z'^{-2} , connecting the relays S^7 and S^8 , respectively, to the trunk wires 54 and 55 and also removing the short-circuit from the condensers C^2 and C^3 . The relay S^3 , Fig. 2, also became deenergized when the called subscriber hung up his telephone, and its armature falling back closes the contacts s^{14} , s^{13} , completes the circuit of the lamp s^{10} causing it to glow, also completing the circuit of the relay S^6 . The relay S^6 now becoming energized attracts its armature and connects battery to the vertical and rotary relays S^7 and S^8 , Fig. 3, by the following paths: battery, wires 44, 45, contacts s^{19} , s^{21} , wire 38, contacts k^1 , k^2 , strand 23, p , j , trunk wire 54; and in Fig. 3, wire 62, contacts s^{28} , s^{29} , of the relay S^9 , wire 66, relay S^7 , wire 68 to ground, and from battery, wires 44, 45, contacts s^{19} , s^{20} , wire 42, contacts k^1 , k^2 , strand 24, p' , j' , trunk wire 55; and in Fig. 3, wire 63, contacts s^{31} and s^{32} of the relay S^9 , wire 67, relay S^8 , wire 68 to ground. Both relays S^7 and S^8 are energized simultaneously over both sides of the trunk wire by battery to ground and attracting their armatures close the contacts s^{23} , s^{26} , completing the circuit of the release magnet W^2 , which when energized restores the connector switch Z'^{-2} to its normal position. The relay S^6 , Fig. 2, remains energized or locked through the contacts s^{17} , s^{18} of the relay S^5 by the following path: battery, wires 44, 45, contacts s^{19} , s^{22} , S^6 , wire 41, contacts s^{18} , s^{17} to ground. It will be seen that battery being placed upon the strand 23, the relay S^3 becoming energized attracts its armature, breaks the contacts s^{13} , s^{14} and would extinguish the lamp s^{10} . This contingency is provided for by the terminal of the lamp leading to the contact s^{14} , being connected to battery by the following path: wire 43, contacts s^{15} , s^{16} , of the relay S^2 , contacts s^{22} , s^{19} of the relay S^6 , wires 45 and 44 to battery. The operator upon seeing both lamps glow-

ing withdraws the plugs from the jacks and the relays S^4 and S^5 become deenergized, the relay S^4 disconnecting the lamp s^{10} and the relay S^5 releasing the relay S^6 , which in turn extinguishes the lamp s^{10} and releases the relay S^2 .

In the foregoing description I have shown two two-way trunks, both being identical, using one as an incoming trunk and the other as an outgoing trunk, so it follows that each trunk can be used either for an incoming or an outgoing call as the case may be.

In the annexed claims I use the terms "line seeking" and "connector" as applied to the switches of the double sets and groups. By the term "line seeking" I mean a switch having the characteristics commonly attributed in the art to a switch designated by that term. The principal characteristic of this type of switch is that its operation is initiated by act of the subscriber and that it thereafter operates independently of all directive control until it finds the sought circuit or line. By the term "connector" I mean likewise that type of switch having the characteristics commonly understood in the art as belonging to a switch so designated. A chief characteristic of such a type of switch is that it is dependent for its operation in whole or in part upon a sustained directive control. Both of these types of switches are so well defined in the art and so commonly known that further definition is believed to be unnecessary.

Having thus described my invention what I claim and desire to secure by Letters Patent is:

1. In a telephone exchange system, a plurality of branch exchanges, a plurality of subscribers' lines terminating in each branch exchange, a selector switch connected to and controlled by each line, a central or clearing-house exchange, and two-way trunk lines connecting the same with the branch exchanges; multiple-terminals for each trunk in a group of subscribers' selector switches, a selector switch for each trunk at a branch exchange and multiple-terminals therein for the subscribers' lines, and means at the central or clearing-house exchange to make connection with the trunk for receiving or sending signals therethrough, each subscriber's selector switch being provided with a cut-off relay actuated when connection is made with the line through a trunk selector switch, substantially as described.

2. In a telephone exchange system, a plurality of branch exchanges, a plurality of subscribers' lines terminating in each branch exchange, a selector switch connected to and controlled by each line, a central or clearing-house exchange, and two-way trunk lines connecting the same with the branch exchanges; multiple-terminals for each trunk in a group of subscribers' selector

- switches, a selector switch for each trunk at a branch exchange and multiple-terminals therein for the subscribers' lines, and means at the central or clearing-house exchange to make connection with the trunk for receiving or sending signals therethrough, each trunk selector switch being provided with a cut-off relay actuated when connection is made with the trunk by a subscriber's selector switch, substantially as described.
3. In a telephone exchange system, a plurality of branch exchanges, a plurality of subscribers' lines terminating in each branch exchange, a selector switch connected to and controlled by each line, a central or clearing-house exchange, and two-way trunk lines connecting the same with the branch exchanges; multiple terminals for each trunk in a group of subscribers' selector switches, a selector switch for each trunk at a branch exchange and multiple terminals therein for the subscribers' lines, terminal spring-jacks and associated signal devices for the trunk-lines at the central office, operators' connecting cord-circuits for interconnecting the trunk-jacks, signals associated with said cord-circuits, means controlled by the subscribers for affecting said signals, and means controlled by the operators for actuating the trunk selector switches, substantially as described.
4. A telephone exchange system comprising branch exchanges with subscribers' lines radiating from each branch exchange, normally interconnected groups of automatic switching apparatus at each branch exchange, a central clearing house exchange, trunk lines therefrom to the apparatus groups at the respective branch exchanges, said trunks being less in number than the number of subscribers' lines, manually controlled means at the clearing house exchange for interconnecting the trunks of the same or different branch exchanges and through them subscribers' lines, and means at each branch exchange whereby a subscriber in calling will set the automatic switching apparatus in motion, to cause the same to select and connect his line with an idle trunk line leading to the clearing house exchange, substantially as described.
5. A telephone exchange system comprising branch exchanges with subscribers' lines radiating from each branch exchange, normally interconnected groups of automatic switching apparatus at each branch exchange, a central clearing house exchange, trunk lines therefrom to the apparatus groups at the respective branch exchanges, said trunks being less in number than the number of subscribers' lines, manually controlled means at the clearing house exchange for interconnecting the trunks of the same or different branch exchanges and through them subscribers' lines, and means at each

branch exchange whereby a subscriber in calling will set the automatic switching apparatus in motion, to cause the same to select and connect his line with an idle trunk line leading to the clearing house exchange and means whereby an operator may set in motion other switching apparatus to select any desired line in the branch exchange in which the apparatus is located, substantially as described.

6. In a telephone exchange system, a plurality of branch exchanges, a plurality of subscribers' lines terminating in each branch exchange, a selector switch for each line, central or clearing house exchange, trunk lines connecting the same with the branch exchanges, multiple terminals for the trunk in the subscribers' selector switches, selector switches for the trunk lines at the branch exchanges and multiple terminals therefor for the subscribers' lines, and operator connective apparatus at the clearing house exchange for interconnecting the trunks, together with means adapted to be temporarily associated therewith to send selected impulses to work the trunk switches at the branch exchanges, substantially as described.

7. In a telephone exchange system, a main clearing house exchange and branch exchanges connected thereto by trunk lines with operators' connective apparatus for the trunks at the clearing house, and a double set of automatic switches at each branch exchange and comprising a set of line seeking and a set of connector switches, the connector switch set controlled over the trunk to select subscribers' lines, and the line seeking set started in operation over the subscribers' lines to select the trunks, substantially as described.

8. In a telephone exchange system, a plurality of subscribers' lines, automatic switching apparatus in groups containing double units comprising connected line seeking and selector switches, operators' manual connective apparatus, trunk lines therefrom to the automatic switching apparatus, a sending device, and means whereby an operator may control said sending device temporarily associated with a trunk line to work the connector switches connected thereto, substantially as described.

9. In a telephone exchange system, a plurality of subscribers' lines, double groups of automatic switches for interconnecting the same comprising a set of line seeking switches for handling incoming calls and a connected set of connector switches for handling outgoing calls, and operators' connective apparatus for interconnecting the line seeking and connector switches through which access is had to a calling and a called subscriber, substantially as described.

10. In a telephone exchange system, sub-

1. Subscribers' lines, double groups of normally connected trunk terminal automatic switches for answering and for calling selection respectively, each of said double groups comprising line seeking and connector switches, and means whereby the operation of the line seeking switches is initiated from the subscribers' line, and operators' apparatus including a telephone set and a controlling device for interconnecting a calling and a called subscriber by means of said switches.

2. In a telephone exchange system, a plurality of subscribers' lines, double groups of automatic switches comprising normally trunk connected line seeking and connector switches for answering and for calling selection respectively, operators' circuits normally disconnected from said switches, means to connect the same in response to a call, and means whereby an operator may actuate the switches of the second group over her circuits when so connected, to establish a connection between lines.

3. In a telephone exchange system, subscribers' lines, branch exchanges, double groups of automatic switches at said branch exchanges comprising line seeking and connector switches, a trunk line connecting said switches with one another and with a main clearing house, and means for effecting connection between two substations by actuating the connector switches from the clearing house over the trunk connections.

4. In a telephone exchange system, subscribers' lines, double groups of automatic switches for interconnecting the same comprising line seeking and connector switches, trunk lines between the switches of the groups, connections from said trunk lines to operators' positions, and means manually controlled by the operators for connecting substations through said trunk connections and said groups of switches.

5. In a telephone exchange system, a plurality of subscribers' lines, a plurality of trunk lines or connective circuits therefor, primary selector switches at one end thereof adapted to connect calling lines with idle trunks, selective switching apparatus at the other end thereof adapted to be controlled so as to connect its trunk with a wanted line, an operator's outfit comprising a telephone set and switch actuating means, a normally open branch connection from said trunk line to the operator's outfit, and means to close said branch operable in responding to a call whereby the operator may ascertain the line wanted and may actuate the said switching apparatus to connect the calling and the wanted subscribers, substantially as described.

6. In a telephone exchange system, subscribers' lines, a plurality of branch exchange trunk or link lines, a plurality of automatic branch exchange switching groups

each group comprising line seeking switching means the operation of which is initiated from the subscribers' lines and which is arranged to automatically connect a calling line to one of said links, and normally connected switching means for selecting a wanted line, a common exchange, and connections from said branch links to said common exchange with means under the control of operators at the common exchange to actuate the said separate and additional switching means for selecting a wanted line at the branch exchanges, substantially as described.

7. In a telephone exchange system, a plurality of automatic branch exchanges, each containing automatic line seeking switches for connecting calling lines to trunks and connected separately operating calling or selective switches, a plurality of subscribers' lines terminating in said automatic branch exchanges, and a main clearing house exchange with means connecting it with each branch exchange and both the primary and selective switches whereby operators thereat may receive all calls from and selectively make all connections at the branch exchanges, substantially as described.

8. In a telephone exchange system, a plurality of subscribers' lines, a line seeking switch the operation of which is initiated by the act of a calling subscriber, a trunk or connective circuit therefor terminating at one end in contacts of the said primary switch, and at the other end in a selector switch adapted when actuated by definite impulses to connect the trunk with a wanted subscriber's line, an operator's equipment comprising a telephone set and a controlling device for said selector switches, a plug terminal for said operator's equipment, and a coöperating jack connected with the trunk, the said selector switch being operable from the operator's equipment only, substantially as described.

9. In a telephone exchange system, a plurality of subscribers' lines, a trunk or connective circuit therefor, automatic line seeking and connector switches for connecting said trunk with calling and wanted lines, respectively, an operator's circuit completely equipped with a telephone set and a switch controlling device separate from the trunk, and switching means to bring said outfit into connection with the trunk, in response to a call.

10. In a telephone exchange system, a main clearing house exchange and branch exchanges connected thereto by trunk lines, with operators' telephones and directive apparatus adapted to be connected to the trunks at the clearing house, and a double set of automatic switches at each branch exchange comprising a set of line seeking and a normally trunk connected set of connector

switches, the connector switch set controlled over the trunks only to select subscribers' lines, and the line seeking set controlled over the subscribers' lines only to select the same trunks, substantially as described.

20. In a telephone exchange system, a main clearing house exchange and branch exchanges connected thereto by trunk lines, with operators' telephones and directive apparatus adapted to be connected to the trunks at the clearing house, a double set of automatic switches at each branch exchange, said double set comprising a set of line seeking and a set of connector switches, subscribers' lines connected in common to switches in both sets, and trunk lines connecting, in common, switches of each set to the main clearing house, one of said sets being controlled over the trunks to select subscribers' lines, and the other set being controlled over the subscribers' lines to select the trunks, substantially as described.
21. In combination, a plurality of electrical transmission lines having different busy and idle conditions and provided with line terminals, a selector switch adapted to connect said lines to another circuit, means for actuating said switch to move from a given normal position successively over the transmission line terminals, and means governed by the condition of any line automatically stopping the movement of said selector switch when an idle line is reached, said means including a self-locking controlling
- 25
- 30

relay having its locking circuit completed through the transmission line test terminals and dependent upon the condition thereof.

22. In combination, a plurality of electrical transmission lines having different busy and idle conditions, a selector switch adapted to connect said lines to another circuit means for actuating said selector switch to move from a given normal position successively over the transmission line terminals and a testing relay governed by the condition of any line and acting to stop the movement of said selector switch when an idle line is reached, said relay after initial energization locking itself through line test terminals.

23. In automatic switching apparatus, selector switches containing multiple test terminals, means for maintaining test potential on terminals that are busy, and a test relay for each switch adapted upon initial energization to connect itself to the test wipe of the switch through a circuit controlled by itself exclusively.

24. An automatic selector switch containing multiple test contacts, a test wiper, and a test relay connected in operation to the test wiper through self-locking means.

In testimony whereof I have affixed my signature in presence of two witnesses.

EDWARD E. CLEMENT.
